UNITED STATES PATENT OFFICE.

JACOB T. ANDERSON, OF NEW YORK, N. Y.

ELECTRIC TANK-SWITCH.

No. 865,185.

Specification of Letters Patent.

Patented June 25, 1907.

Application filed May 17, 1906. Serial No. 317,287.

To all whom it may concern:

Be it known that I, JACOB T. ANDERSON, a citizen of the United States, and residing at New York, in the county of New York and State of New York, have invented certain new and useful Improvements in Electric Tank-Switches, of which the following is a specification, such as will enable those skilled in the art to which it appertains to make and use the same.

This invention relates to electric switches and particularly to automatically opening and closing switches which are actuated upon by floats and counter-weights and which are specifically devised for starting and shutting down electric motors and pumps for filling tanks with water or other fluids, and the object of my invention is to provide an apparatus whereby a rapid make and break of the switch is effected by the oscillatory movements of a switch arm respectively corresponding to the low or highwater level in a tank to which my apparatus is connected; and a further object being to provide an apparatus which is simple of construction, effective in its operation and positive in its action; and with these and other objects in view the invention consists in a device of the class specified constructed as hereinafter described and claimed.

The invention is fully disclosed in the following specification, of which the accompanying drawing forms a part, in which the separate parts of my improvement are designated by suitable reference characters in each of the views, and in which;

Figure 1 is a side view of my apparatus with the front plate of the cover removed thereby exposing the interior of the same; Fig. 2 an end view looking toward the electric switch contact points; and, Fig. 3 an end view in the opposite direction. Fig. 4 a side view of a pivoted weight which I employ; Fig. 5 a view of the side of said weight opposite to that shown in Fig. 4; and, Fig. 6 a transverse section on the line 6--6 of Fig. 5.

In the drawings, I have illustrated at *a* a base which carries the two switch contact points *b* and *c* to which the terminals *d* and *e* of an electric circuit are connected. This circuit includes in the usual manner and not shown in the drawing a source of electric supply, rheostat and electric motor which latter is designed to operate a pump for the purpose of filling a tank such as is used for storage purposes in connection with buildings, railroads, etc., and the switch apparatus shown

in the drawing is designed to start and stop said pump automatically for the purpose of refilling the tank as soon as the water level has reached a predetermined low point. 60 These switch contact points *b* and *c* are insulated from each other in the usual manner and a knife blade contact *f* which is pivoted at *g* can by oscillating movements imparted thereto enter into or leave the contact points *b* and *c* so as to open or close the circuit connected therewith.

The pivot *g* is a shaft which is stationary in its bearings *h*, and upon this pivotal shaft *g* oscillates a double arm lever *i* to one end of which the aforementioned knife blade *f* is attached and is insulated therefrom in the usual manner by a fiber, mica or asbestos plate *k*, while the other end is a weighted arm *l* which is provided with an off-set *m* designed 75 to engage with a lug *n* of a second oscillating weight *o* which is also pivoted on the stationary shaft *g*. The lever arm *i* is provided with an inclined stop *j* against which impinges the lug *n* of the weight *o* whenever said 80 weight is thrown over and toward said arm, and this depresses the lever arm *i* and causes the knife blade *f* to enter the switch contact points *b* and *c* as illustrated in dotted lines in Fig. 1 of the drawing. The extent of the oscillatory motion of the lever arm *i* is limited in one direction by the contact points *b* and *c*, and in the opposite direction by means of the stationary stop *p*. The oscillating weight *o* is brought from one extreme of its motion to 85 the other by means of the pin *q* which is stationary with a rope wheel *r*, and which pin impinges while traveling in either direction against the straight contact edge *s* of the weight *o*. The rope wheel *r* is also oscillated 90 upon the stationary pivotal shaft *g* and motion is imparted thereto by means of a weight *t* at the end of the rope *u* which causes a float *v* fastened to the other end of the rope *u* to fall when water is drawn off from the 95 tank. Somewhat prior to the time that the water level in the tank has reached its predetermined lower level, the weight *t* comes to rest on a shelf or support which is not shown, the rope *u* becomes slack, and as soon as the float *v* becomes suspended its weight causes the rope wheel *r* to partially rotate, the pin *q* travels from the position designated by *g* in Fig. 1 to the position designated by *x* and engages with the straight edge *s* of the pivoted 110 weight *o*, the latter rotates until the pin *q* has reached the position *y*, when the weight *o* by

means of its force of gravity will fall forward and its lug *n* will impinge upon the stop *j* of lever arm *i* and carry the same and its attached knife blade *f* downwardly and thereby make the desired connection between the switch contact points *b* and *c*. A further oscillatory motion of the rope wheel *r* is arrested by the pin *q* coming again in contact with the straight edge *s* of weight *o*. A reverse movement and a break between the switch contact points *b* and *c* takes place as soon as the tank has been filled, the water raising the float and the weight *t* on end of rope *u* causes the rope wheel *r* and the pin *q* to revolve backwardly until it strikes the edge *s* of the pivoted weight *o*, and in its further motion disengages the knife from contacts *b* and *c* and brings the weighted end *l* of lever *i* to rest against the stop *p*.

20 A cover *z* incloses the entire apparatus so as to make the same water and dust proof which permits my apparatus to be placed in any exposed position without causing interference in its action through the accumulation of dust, water, etc.

25 It will thus be seen that by means of my improved tank switch the action of making a positive and rapid make and break at the switch is effectively attained for the purpose for which the same is described.

30 I do not limit the use and application of my invention solely to tank switches operated by means of float and counter-weight, but any other means of imparting rotary motion to the rope wheel and the thereto connected mechanism such as by pulling on the rope or by transmitting motion to the wheel by gear and chain, or gear and shaft, or in any other manner may be employed to 35 set the switch mechanism in operation.

40 Having fully described my invention, what I claim as new and desire to secure by Letters Patent, is:—

1. An electric switch having a pivoted

double arm lever with knife blade contact 45 fixed to one arm and insulated therefrom, means for depressing either arm alternately in order to make or break contact between the terminal points of a circuit, such means consisting of an oscillating rope wheel with a 50 pin attached thereto which latter will impart oscillatory motion to a pivoted weight which is brought to bear against one or the other arm of the pivoted lever so as to depress and hold such arm in its depressed position, substantially as shown and described.

2. An electric tank switch having terminal contact points of a circuit, a pivoted double arm lever, devices for depressing one or the other arm of the lever in order to close or 55 break the circuit by the insertion or withdrawal of a knife blade forming part of one end of the lever, such devices being set in motion by means of a rope wheel, a contact pin attached thereto, an oscillating weight 60 caused to bear against either arm of the lever and a rope transmitting rotary motion to the rope wheel and the thereto connected mechanism, substantially as shown and described.

3. In an electric tank switch, a float fastened to one end of a transmission rope and a counter-weight fastened to the other end of the rope, an oscillating rope wheel, means for causing a pivoted weight to oscillate and to bear against one or the other end of a 75 double arm pivoted lever which latter is provided with an insulated knife blade arranged to enter into or to be withdrawn from the terminal contact points of a circuit, substantially as shown and described.

80 In testimony that I claim the foregoing as my invention I have signed my name in presence of the subscribing witnesses this 16th day of May, 1906.

JACOB T. ANDERSON.
